CARD TABLE ATTACHMENT

Katherine M. McGinty, Birmingham, Ala.

Application April 30, 1931, Serial No. 534,036
Renewed June 3, 1933

2 Claims. (Cl. 273—150)

This invention relates to game accessories, and pertains particularly to a device designed for use upon a card table.

The primary object of the present invention is to provide a novel device for use upon card tables, where the same are used on trains, boats, terraces, porches or any place where there might be interference by the wind, for holding in place those cards which must be laid upon the table as, for example, the cards played, the cards of a dummy hand, etc.

Another object of the invention is to provide a card holding device adapted to be detachably engaged with the top of a card table, which is of simple design and which may be readily detached to be moved about from one side of the table to the other.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:

30 Figure 1 is a view in top plan of a card table showing the device embodying the present invention applied thereto.

Figure 2 is a sectional view taken on the line 2—2 of Figure 1.

35 Figure 3 is a sectional view taken on the line 3—3 of Figure 1.

Figure 4 is a sectional view taken on the line 4—4 of Figure 1.

Referring more particularly to the drawing, 40 wherein like numerals of reference indicate corresponding parts throughout the several views, the numeral 1 indicates a card table to which the present invention is shown applied.

The invention consists of a set of members, 45 one of which might be termed the dummy hand and played card holder, and is indicated by the numeral 2. Other elements of the device are indicated by the numeral 3 and are designed to hold other groups of cards on the table such, 50 for example, as the cards removed as tricks taken, while still another element of the set, which is indicated by the numeral 4, is designed to hold an additional pack of cards on the table.

The dummy hand holder 2 comprises an 55 elongated metal strip 5 which is of a length to

extend the full width of the card table top. Each end of this metal strip is turned back upon itself to form a resilient finger 6 which engages the under surface of the table top, the resilient fingers at the ends of the strip 5 engaging the under surface of the table at opposite edges, as shown.

Formed integral with the strip 5 along one longitudinal edge are four relatively long resilient arm strips 7 which are divided into two pairs, as illustrated, and disposed between these strips 7 is a central longer resilient strip 8, the free end of which extends to the center of the table. Each of the strips 7 is designed to hold the cards of one suit of a dummy hand beneath its free end thereof, while the central strip 8 is designed to hold beneath its free end the cards played onto the table.

The elements 3 are in the form of relatively short resilient strips, each of which has one end turned back to form a spring finger 9 which engages about one edge of the table top, as shown in Figure 3. These resilient strips or arms 3 are designed to hold in place on the table the cards or tricks taken by the players.

The element 4 is designed to hold an extra deck of cards and comprises, as shown in Figure 4, a relatively long body 10 which has the central portion offset or raised, as indicated at 11, so that a deck of cards may be conveniently placed in this raised portion and secured to the table by the turned back finger portion 12 which forms an integral part of the elongated body 10, as shown, and which is designed to receive and resiliently hold an edge of the table body.

From the foregoing description it will be readily seen that by the use of a set of the character herein described a game of cards may be played out of doors even where a strong breeze is blowing, and no difficulty will be experienced by the players in keeping the cards in place upon the table.

Having thus described the invention, what is claimed is:

1. An attachment for card tables, comprising an elongated flat strip of material designed to extend transversely of the surface of a card table, means at the ends of said strip of material for engaging opposite edges of the table to removably hold the strip in position thereacross, and a plurality of resilient arms carried by said strip and extending from one side thereof to lie upon the surface of the table to maintain cards in position thereon.

2. An attachment for card tables, comprising

an elongated flat strip of material designed to extend transversely of the surface of the table, resilient fingers formed integral with the ends of said strip and disposed in spaced parallel relation thereto to frictionally engage over opposite edges of a table, a plurality of flat resilient arms formed integral with said strip and all extending

from one side edge thereof, and an arm of greater length than the first mentioned arms carried by and extending from the strip from the same side thereof as the first mentioned arms, each of said arms being designed to hold a card in position 80 on the table surface.

KATHERINE M. McGINTY.
